RADIO POSITION FINDING

David G. C. Luck, Hightstown, N. J., assignor to
Radio Corporation of America, a corporation
of Delaware

Application November 2, 1942, Serial No. 464,178

5 Claims. (Cl. 250—1.68)

1

This invention relates to radio position finding, and more particularly to determining the position of a mobile craft with respect to a plurality of fixed stations by observing the propagation times required for radio waves to travel between said craft and said stations.

It is an object of this invention to provide an improved method of and means for deriving an indication of the distance between two stations.

Another object is to provide an improved method of and means for utilizing a plurality of such indications to automatically plot the map position of a mobile station with respect to two or more fixed stations.

These and other objects will become apparent to those skilled in the art upon consideration of the following description, with reference to the accompanying drawings, of which Fig. 1 is a schematic block diagram of a distance indicating system, according to the invention, Fig. 2 is a block diagram of the echo station of Fig. 1, and Fig. 3 is a schematic block diagram of a complete system for providing automatically an indication of the map position of a mobile station with reference to two fixed stations. Similar reference characters designate similar elements in the drawings.

Referring to Fig. 1, the mobile station includes an oscillator 1 coupled through an amplifier 3 to an antenna 5, and through a modulator 7 to a second antenna 9. The oscillator 1 is frequency modulated by the output of a sawtooth wave generator 11. A second oscillator 13 is connected to the modulator 7. An antenna 15 is connected to a receiver 17. The output circuit of the receiver 17 is connected to a frequency responsive indicator, such as an averaging cycle counter 19 and a meter 21. An echo or fixed station is indicated by the block 6.

The fixed station (Fig. 2) includes a receiver 25 and a transmitter 23. The output circuit of the receiver 25 is connected through a modulator 27 to the transmitter 23. A local oscillator 29 is connected to the modulator 27.

The operation of the system is as follows: The receiver 25 and the amplifier 3 are tuned to one carrier frequency, f , and the receiver 17 and the transmitter 23 are tuned to another carrier frequency, $(F+F)$. The oscillators 13 and 29 are both adjusted to operate at the frequency F . The frequency of the oscillator 1 is cyclically varied about the carrier frequency f as a mean, by the sawtooth output of the generator 11, starting each cycle at its minimum value f_0 and increasing linearly at a rate df/dt which depends

on the slope of the sawtooth wave. This variable frequency signal is amplified by the amplifier 3 and transmitted from the antenna 5 at the velocity of light, c . Thus if the frequency transmitted at the instant t is f_0 , the frequency of the signal reaching the echo station 6 will be f_0 at a later time t' . The interval $t'-t$ is the propagation time of the signals from the mobile station to the echo station.

10 The signal received at the echo station is converted in the modulator 27 to the carrier frequency $f+F$, and retransmitted, after a short delay period, T , by the transmitter 23. The retransmitted signal carries the same frequency variations as the original signal; it is merely shifted in frequency by the amount F . The signal f_0+F is thus retransmitted at the time $t'+T$. The time required for this signal to return to the mobile station is again the interval $t'-t$, assuming that the movement of the mobile station is negligible in the time $2(t'-t)$. The total time from the transmission of the frequency f_0 to the return of the frequency f_0+F is thus $2(t'-t)+T$. Since the signals travel at the velocity of light, c , the time $t'-t$ is the distance, d , between the two stations, divided by c . The total time is

$$2\frac{d}{c} + T$$

30 During this interval, the frequency of the oscillator 1 changes at the rate

$$\frac{df}{dt}$$

35 so that at the time the frequency f_0+F is received at the antenna 15 from the echo station 6, the frequency of the oscillator 1 is

$$f_0 + \frac{df}{dt}(2d/c + T)$$

This signal is converted by the modulator 7 and oscillator 13 to a frequency

$$f_0 + \frac{df}{dt}(2d/c + T) + F$$

45 and transmitted over a negligible (negligible because both devices are located on the mobile station) distance to the antenna 15. The input to the receiver 17 thus comprises two voltages, differing in frequency by the amount

$$\Delta f = \left(f_0 + \frac{df}{dt}(2d/c + T) + F \right) - [f_0 + F] = 2d/c \frac{df}{dt} + T \frac{df}{dt}$$

providing a beat note of this frequency in the output of the receiver. Since the quantities

$$\frac{df}{dt}$$

and T are design constants of the system, and c is a constant, the beat frequency Δf is varied only with variations in the distance d .

The beat frequency voltage controls the counter 19 to provide a direct current proportional to Δf , deflecting the meter 21 by a corresponding amount. The distance d is equal to

$$c/2 \left(\frac{\Delta f}{df/dt} - T \right)$$

The indication of the meter 21 is thus related linearly to the distance d . The frequency f_0 may be, for example, 300 megacycles per second, df/dt 30 megacycles per second per second, the saw-tooth frequency 100 cycles per second, and the retransmission delay T a few microseconds, so that T may be neglected for all but very short distances. These values are suitable for the measurements of distances up to which the direct transmission path becomes blocked by the curved surface of the earth.

A value of d given by a system such as that of Fig. 1 establishes the position of the mobile craft as on a circle of radius d about the fixed echo station. By using two suitably located echo stations, each retransmitting on a separate channel, and a receiver and frequency meter at the mobile station for each channel, the position of the mobile station can be established as at an intersection of the two circles corresponding to the two fixed station locations and the two corresponding values of d . To give a check, and also to determine which of the two intersections is relevant, a third fixed station and a third channel may be used. The circles may be plotted on a map or chart to determine the position of the mobile station.

The plotting may be done automatically by use of a multiple gun cathode ray tube arranged as shown in Fig. 3. The mobile station includes an oscillator 1, amplifier 3, antennas 5, 9 and 15, modulator 7, oscillator 13, receiver 17, and counter 19, connected like the correspondingly designated parts of the system of Fig. 1. A second channel, including a modulator 107, oscillator 113, receiver 117, and counter 119, is arranged in the same manner as the first channel, but is operated at a different conversion frequency F' . The counters 19 and 119 may be of the type described in Schwartz, U. S. Patent 2,137,859. The outputs of the cycle counters 19 and 119 are direct voltages proportional respectively to the distances d and d' of the echo stations 6 and 106 from the mobile station.

A double gun cathode ray tube 31 is connected to a power supply 33. One set of deflection circuits 34, 35 is connected to an adjustable centering control circuit 37. The other deflection circuits 39 and 41 are similarly connected to a centering control circuit 43.

An oscillator 45 is connected through modulators 47 and 49 to phase splitting circuits 51 and 53 respectively. The two-phase outputs of the circuits 51 and 53 are superimposed on the centering voltages provided by the circuits 43 and 37 to the respective deflection circuits.

The phase splitting and centering circuits associated with each deflection system of the cathode ray tube 31 may be identical with those shown on Page 365 of RCA Review, vol. VI, No. 3, Janu-

ary, 1942, in the section marked "cathode ray indicator" of the drawing, Figure 17.

In operation, the two-phase voltages derived from the output of the oscillator 45 by the phase splitters 51 and 53 are applied to the respective deflection circuits to provide circular traces 55 and 57 of the electron beams upon the screen of the tube 31. These traces are centered about points 59 and 61 respectively, which are adjusted by means of the centering controls 37 and 43 to positions corresponding to the map positions of the echo stations 6 and 106. The radii of the traces 55 and 57 depend on the quantities of the output of the oscillator 45 which are applied to the respective deflection circuits. These are controlled by the modulators 47 and 49 in response to the D.-C. outputs of the respective counters 19 and 119. Thus the position of the mobile station is indicated at one of the points of intersection 63 and 65 of the two traces.

Thus the invention has been described as an improved radio position finding system. Frequency modulated signals are radiated from a mobile station, picked up, changed in frequency and retransmitted by a fixed station. The frequency of the retransmitted wave is compared at the mobile station with that of the wave being transmitted from the fixed station. The difference is related to the time of travel of the signals between the two stations, and provides a direct measure of the distance. Two or more such systems are used to determine the position of the mobile station with respect to the fixed stations. The position may be plotted automatically on a cathode ray tube by tracing circles, of radii proportional to the respective distances, centered about points corresponding to the map positions of the fixed stations.

I claim as my invention:

1. A radio distance measuring system comprising a control station and an echo station, means at said control station for radiating two similarly frequency modulated signals differing in frequency by a predetermined amount, a receiver at said echo station tuned to respond to one of said signals, a frequency changer connected to said receiver and adjusted to change the frequency of the output thereof by said predetermined amount, a transmitter connected to said frequency changer to radiate said frequency changed signal, a receiver at said control station tuned to respond to said reradiated signal and to the other of said radiated signals, and beat frequency responsive means connected to said receiver to respond to the difference in frequency of said latter two signals.

2. A radio distance measuring system comprising a control station and an echo station, means at said control station for radiating a frequency modulated signal and for generating a second signal differing from said radiated signal by a predetermined frequency, means at said echo station tuned to receive said radiated signal and to radiate a similarly modulated signal at frequency differing from said received signal by said predetermined frequency, means at said control station tuned to receive the signal transmitted from said echo station, and means responsive to the difference in frequency between said latter signal and said second signal.

3. A radio position indicating system comprising a control station, and a plurality of spaced echo stations, means for radiating a frequency modulated signal from said control station, means at each of said echo stations for receiving said

signal, changing the frequency thereof by a predetermined amount, and retransmitting said changed signals, receivers at said control station tuned to respond to the signals radiated by the respective echo stations, means for comparing the output of each of said receivers with the signal radiated from said control station to derive control voltages proportional to the respective distances of the echo stations from the control stations; a cathode ray tube, deflection circuits including an oscillator and phase splitting circuits connected to produce circular sweeps of the beam of said cathode ray tube, and variable gain amplifiers connected in said deflection circuits and connected to said comparing means to be varied in gain by said control voltages.

4. A radio position determining system comprising a control station and a plurality of spaced echo stations, means for radiating a frequency modulated signal from said control station, means at each of said echo stations for receiving said signal, changing the frequency thereof by a predetermined amount, and retransmitting said changed signals, a cathode ray tube at said control station, deflection circuits for said tube including an oscillator and phase splitting circuits connected to produce a plurality of circular scanning patterns on the face of said tube, amplitude control means connected in each of said deflection circuits, and means responsive to said retransmitted signals and to said initial signal to control said amplitude control means.

5. The method of indicating in the form of intersecting circular traces the position of a mobile station with respect to the positions of a plurality of spaced fixed stations on the luminescent screen a cathode ray tube of the oscilloscope type having conventional deflection means, including the steps of radiating a frequency modulated signal from said mobile station, receiving said signal at each of said fixed stations, reradiating said frequency changed signals respectively from each of said fixed stations, receiving said reradiated signals at said mobile station, comparing the frequency of each of said received reradiated signals with that of said initial signal to derive control voltages proportional to the frequency differences, producing circular traces on said screen of said cathode ray tube, and controlling the respective radii of said traces in accordance with said control voltages.
